Attorneys

UNITED STATES PATENT OFFICE

ERNEST A. PODD, OF HOUSTON, TEXAS

SPREADER CLAMP

Application filed August 14, 1930. Serial No. 475,315.

This invention relates to new and useful improvements in a spreader clamp.

One object of the invention is to provide a spreader clamp of the character described, 5 designed for use in construction work for holding parts together and particularly for use in connection with false work for holding the sides of concrete forms in position to receive plastic concrete and to hold the same 10 until the concrete sets and hardens sufficiently to support itself.

This type of spreader clamp is particularly useful for the purpose of maintaining forms in position for molding concrete 15 beams, girders and the like, although it is capable of general application and use for holding parts in desired relation.

A further feature of the invention resides in the provision in a spreader clamp of 20 means for maintaining the securing wedges in position to the end that they will not become loose, due to vibration.

A still further feature of the invention resides in the provision of a novel type of 25 spreader clamp having weakened lines so that the projecting ends may be broken off flush with the outer surface of the molded wall or beam, or may be broken off beneath such surface.

30 A still further feature of the invention resides in the provision of a novel type of key for the purpose of providing a keyway in the molded object adjacent the body of the clamp so as to permit the breakage of the 35 projecting ends of the body beneath the surface of said molded object, said keys being specially formed so that they will be securely held in place when the clamp is in use and can be readily removed when it is 40 desired to dismember the false work.

With the above and other objects in view, the invention has particular relation to certain novel features of construction, arrangement of parts and use, an example of which 45 is given in this specification and illustrated in the accompanying drawing, wherein:—

Figure 1 shows a fragmentary horizontal 50 sectional view, taken on the line 1—1 of Figure 2, of a form maintained in position by the type of spreader clamp described.

Figure 2 shows a fragmentary vertical sectional view thereof, taken on the line 2—2 of Figure 1.

Figure 3 shows an enlarged vertical sectional view taken on the line 3—3 of Figure 2.

Figure 4 shows a fragmentary plan view of the body of the spreader clamp.

Figure 5 shows a longitudinal sectional view thereof, taken on the line 5—5 of Figure 4.

Figures 6 and 7 show fragmentary plan views respectively of slightly modified forms.

Figure 8 shows a plan view of the outer 65 end of the clamp body showing the keyway therethrough, and

Figure 9 shows a vertical sectional view thereof taken on the line 9—9 of Figure 8, 70 showing the wedge therein.

Referring now more particularly to the drawing wherein like numerals of reference designate similar parts in each of the figures, the numerals 1, 1 designate the opposite sides of the concrete form into which the plastic concrete is poured and molded. This form will have the usual bottom (not shown) to receive the poured concrete and to support the same. Abutting the outer sides of the sides 1, 1 of the form are the vertical 75 studding 2, 2 and against the outer sides of the studding there is the horizontally disposed waling formed of the timbers 3, 3 preferably arranged in pairs the timbers of each pair being spaced apart as clearly 80 shown in Figure 2. Adjacent the upright studding 2, 2 the side walls are provided with openings 4, which are transversely aligned and which are also aligned with the spaces 5, between the timber 3 as illustrated in Figures 1 and 2.

A construction in connection with which the spreader clamp may be used has been above described a preferred form of the construction, and a method of the use of the 95 clamp itself will now be described and explained.

The body of the clamp consists of a long strip of metal 6, preferably of channel iron, having the end slots 7, 7 forming keyways. 100

Spaced inwardly the required distance from each end of the body 6 are the spreader lugs 8, 8 which are thrown out from the material of the body. These lugs are spaced a distance apart over all equal to the thickness of the concrete beam or wall to be formed and they are located equal distances from the longitudinal central line of such beam or wall. When the false work and the side 10 forms 1, 1 are erected in place the spreader clamp may be inserted through the openings 4 and the spaces 5 with the key slots 7 extending out beyond the waling 3 and the lugs 8 will engage the inner sides of the 15 form being constructed as shown in Figure 2. The openings 4 above the body of the clamp may then be plugged up in any suitable manner so that the plastic material will not escape from the form. Suitable washers 9 are then fitted over the ends of the 20 clamp body against the waling 3 and the wedges 10, 10 are then driven through the keyways and bear against said washers 10 and serve to hold the clamps securely in 25 place. In order to hold the wedges against displacement by reason of vibration or otherwise the inner sides of the intermediate portions of the keyways 7 are serrated thus forming the teeth 11 and as the wedges are 30 driven home, these teeth will be bent or inclined correspondingly and will bite into the wedges and securely hold the same against displacement.

It is to be understood that a number of 35 clamps will be used in the construction and they will be spaced apart the required distance so as to securely sustain the load to which the form will be subjected.

When the wedges 10 are driven securely 40 in place the lugs 8 will be drawn tightly against the inner sides of the walls thus spreading and holding the form walls the required distance apart and there holding them until the clamps are released and removed, after the concrete is set.

If desired keys 12 may be fitted inwardly through the openings 4 so to substantially close said openings. The inner ends of these keys project inwardly beyond the sides 1, 1 45 so that plastic material will form around them. These keys are each provided with a barb 13 to engage with the corresponding wall 1, when the keys are driven into place, to hold a corresponding key against displacement due to vibration or other cause. The outer end of each key 12 has a projection 14, spaced from the corresponding wall and so that an implement may be inserted between said projection and wall and the key 50

60 unseated and removed when desired. In dismantling the form the keys 12 will first be withdrawn and when the form is dismantled the ends of the clamp bodies 6 may be broken off along the weakened lines 15 65 flush with the outer surface of the walls 1

and said walls may then be readily removed. The ends of the strips 6 remaining may then be broken off at the inner ends of said keyways formed by the keys 12 and the keyways then filled with a plastic concre- 70 tious material, and troweled smooth.

In case the keys 12 are not used the clamp bodies 6 may be weakened at the points 16 so as to be readily broken off flush with the outer surface of the wall, or beam, or at the 75 points 17 so that they may be broken off just beneath the surface of the wall, or beam, and in this latter case the breakage of the clamp body will occur only a short distance beneath the surface and the broken off end may be covered up and protected by plastic concrecious material troweled flush with the outer surface of the beam or wall. In case the keys 12 are employed the clamp body 6 should be scored or weakened at a point in- 80 wardly from the corresponding lug 8 as in- 85 dicated by the numeral 18 in Figure 7. In dismantling the form the wedges 10 may be easily driven out and the false work and form removed and the ends of the clamp body 6 broken off flush with the face of the 90 molded beam or wall or back into the concrete as hereinbefore explained.

The drawing and description disclose 95 what is now considered to be a preferred 95 form of the invention by way of illustration only while the broad principle of the invention will be defined by the appended claims.

What I claim is:

1. The combination with a form for mold- 100 ing concrecious material and having aligned openings, of a clamp formed of a strip of material having end keyways and fitted through said openings, wedges through said keyways, means interlocking with said wedges and holding them in place, keys fitted inwardly through said openings ad- 105 jacent said strip and whose inner ends pro- ject into the form and means on the keys 110 engaging with the form to retain the keys against accidental displacement.

2. The combination with a form for mold- 115 ing concrecious material and having aligned openings, of a clamp formed of a strip of material having end keyways and fitted through said openings, wedges through said keyways, keys fitted inwardly through said openings adjacent said strip and whose inner ends project into the form and means on the 120 keys engaging with the form to retain the keys against accidental displacement.

In testimony whereof I have signed my name to this specification.

ERNEST A. PODD.
